UNITED STATES PATENT OFFICE.

RUFUS R. NOBLIT, OF MEADVILLE, PENNSYLVANIA.

TORPEDO PLACER.

Application filed May 18, 1927. Serial No. 192,382.

This invention relates to torpedo placers for railways and its general object is to provide a torpedo placer which can be used to place a torpedo on a rail from the rear end 5 of a moving train in an efficient, easy and expeditious manner and with very little effort on the part of the operator.

A further object of the invention is to provide a torpedo placer that is capable of 10 carrying at least two torpedoes so that a number of torpedoes can be placed on a rail at an appropriate distance apart and in quick succession.

Another object of the invention is to provide 15 a torpedo placer that is simple in construction, inexpensive to manufacture, yet will perform its intended function for a prolonged period of time.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several 30 views, and in which:

Figure 1 is a view illustrating the manner in which my torpedo placer is used to secure a torpedo to a rail.

Figure 2 is an enlarged fragmentary sectional view showing the application of a 35 torpedo in my placer.

Figure 3 is a perspective view of one of the ends of my placer.

Referring to the drawings in detail the 40 reference numeral 1 indicates the handle of my torpedo placer which has secured to each end and upon opposite sides thereof arms which cooperate with each other to provide a fork in a manner as best shown in Figure

45 1 of the drawings. Each of the arms include attaching plates 2 and 3 which are secured to the handle through the instrumentality of rivets or other fastening means 4. The arms from the attaching plates 2 and 50 3 are flared outwardly to provide diverging intermediate portions 5, and from the diverging intermediate portions the arms extend in parallel portions 6 which have their free ends curved outwardly in opposed directions in a manner as best shown in Figure 55 2 of the drawings.

The parallel portions are provided with longitudinally disposed slots 7 which terminate adjacent each end of these parallel portions and the lower end wall of the slots are 60 recessed to provide shoulders 8 for the purpose of receiving the ends of the usual spring A for the holder of the torpedo B as best shown in Figure 2 of the drawings.

From the above description and disclosure 65 of the drawings, it will be obvious that I have provided a torpedo placer which is adapted to have fixed in each end thereof through the medium of the shoulders 8 a torpedo and by employing the arms on each end 70 of the handle 1, the torpedo can be arranged in each end of the handle which is of sufficient length to allow a person to apply a torpedo to a rail from the rear end of a moving train, as it will be apparent that when 75 the one torpedo is placed on the rail, the handle can be reversed to apply the other torpedo, and due to the movement of the train, the torpedoes will be sufficiently spaced from each other so as to give an appropriate signal. By arranging the spring A of the holder of the torpedo B in the manner as shown in Figure 2, it will be obvious 80 that the torpedo can be readily applied to the rail C by merely allowing the intermediate portion of the spring A to engage the rail and with slight downward pressure of the handle, the ends of the spring A will be released from the shoulders 8 with the result the spring will be securely clamped to 85 the rail so as to be arranged in the path of a following train.

It is thought from the foregoing description that the advantages and novel features of my invention will be readily apparent. 95

I desire it to be understood that I may make changes in the construction and in the combination and arrangement of the several parts, provided that such changes fall within the scope of the appended claims. 100

What I claim is:

1. A torpedo placer of the character described comprising a handle, cooperating arms secured to the ends of said handle to provide a fork at each end thereof, said arms 105 being slotted, shoulders formed in said slots and being adapted to receive a torpedo.

2. A torpedo placer of the character described comprising a handle, arms arranged in pairs and secured adjacent the ends of said handle in a manner to provide a fork 110 at each end, parallel portions included in

said arms and being provided with longitudinally disposed slots, a shoulder arranged at the outer ends of each slot and said parallel portions terminating in outwardly flared free ends.

3. A torpedo placer of the character described comprising a handle, arms secured to the ends of said handle and being arranged in pairs to provide a fork, attaching portions included in said arms, fastening means passing through said attaching

portions and ends of said handle respectively for securing the arms thereto, diverging intermediate portions formed with said attaching portions, parallel portions formed with said diverging intermediate portions and being provided with longitudinally disposed slots, shoulders formed in one of the ends of said slots and said parallel portions terminating in outwardly flared free ends. 15 20

In testimony whereof I affix my signature.
RUFUS R. NOBLIT.
